UNITED STATES PATENT OFFICE.

JAMES E. WILSON, OF BRIDGEPORT, CONNECTICUT.

LATHE-CHUCK.

SPECIFICATION forming part of Letters Patent No. 234,216, dated November 9, 1880.

Application filed May 12, 1879.

To all whom it may concern:

Be it known that I, JAMES E. WILSON, of Bridgeport, county of Fairfield, and State of Connecticut, have invented new and useful improvements in Lathe-Chucks, which improvements are fully set forth in the annexed specification and in the accompanying drawings.

The object of my invention is the construction of an improved lathe and drill chuck of more than ordinary clamping power, arranged to be operated without the use of keys or levers; and it consists in the arrangement, in such a chuck, of a system of differential gearing for operating mechanism to cause the proper convergent and divergent movement of the jaws of the chuck.

Referring to the drawings, which consist of two sheets and eight figures, Figure 1 is a view of my chuck complete. Fig. 2 is an elevation showing the chuck-case and shaft in section, and other working parts connected with the latter. Fig. 3 is a side elevation of the shaft. Fig. 4 is a perspective view of the case. Fig. 5 is a face view of the scroll-plate, showing the jaws thereon. Fig. 6 is a side view of one of the jaws. Fig. 7 is an end view or elevation of the shaft, on an enlarged scale, showing the gears in position thereon; and Fig. 8 is an end view of the shaft, also on an enlarged scale.

In the drawings, A is the shaft. b and c are gears. d is a pinion. h is a scroll-plate. i are jaws. B is the case. e is a sleeve-nut. n is a face-plate. D is an eccentric on the end of shaft A. o is an end of shaft A projecting beyond eccentric D. r is a collar on shaft D. t is a set-screw. v is a pin passing through gear c and into scroll-plate h.

Like letters refer to like parts in the several figures.

The jaws i of my chuck are constructed with projections on one side, as shown, which fit into the grooves on the scroll-plate h. Said jaws are of a width equal to that of the radial cuts in the end of case B, Fig. 4, and they are caused to move therein to and from the center of the chuck by the revolution of the scroll-plate. The other internally-operating parts of the chuck consist of the hollow shaft A, having thereon a collar, r, an eccentric, D, and a projecting end, o, of two annular gears, b and c, and of a pinion, d.

The above-named parts are inserted in case B from the bottom in the order shown in Fig. 2, with projection o on shaft A entering into the center hole in scroll-plate h, bringing the face of scroll-plate h up against the under side of the thick end in which the jaw-grooves are formed, as seen in Fig. 4, and pin v is inserted through coinciding holes in gear c and scroll-plate h, as shown. The said parts are retained in case B by the screw-collar e, screwed into the lower end of case B up against the under side of collar r on shaft A.

In the periphery of the annular gear b is cut a notch, as shown, into which the end of screw t in the side of case B enters.

After having assembled the parts of the chuck as above set forth and placed the jaws i in their grooves in the end of case B, with their projections in the grooves on the scroll-plate, I secure plate n against the end of the chuck, as shown in Figs. 1 and 2.

The annular ring-gears b and c are not constructed with an equal number of teeth in them. In this case gear b has thirty-one teeth and gear c has thirty, it being requisite for differential effects that one gear should have more teeth than the other.

It is obvious that other combinations of differential gears than the specific one herein shown and described might be constructed and applied to a chuck to serve the purposes of this invention. For instance, the annular ring-gears b and c may be made with an equal number of teeth in each, and the differential element be confined to pinion d, in which the number of teeth working in gear b would differ from the number working in gear c, and vice versa.

Pinion d is made with a face as wide as the combined width of the two gear-faces of gears b and c, and with teeth to conform to those on said two gears.

It will be observed that when gears b and c are laid one upon the other, as in Fig. 7, a small number of the teeth thereon are in a corresponding position, or very nearly so, and that from said position each way around the circle the relative position of the teeth of the gears b and c differs increasingly to a point opposite their coinciding points, where a full tooth of gear b is shown between two of the teeth of its overlying gear c.

Shaft A is made with a central passage through it to receive the end of a proper mandrel to fit the bored end of a lathe-spindle, and to allow of freely passing the shank of a drill into the chuck between the jaws. Its collar r is made of the diameter of the interior of the case B. Next above collar r on said shaft is the eccentric D, arranged to receive pinion d and to allow it to revolve freely thereon. Up above eccentric D is the central projection, o, which, when the parts are assembled, as in Fig. 2, becomes a stud on which the scroll-plate h and gear c, pinned thereto, revolve.

The operation of my chuck is as follows: The case being grasped by the hand and held while the shaft A is revolved, it will be observed that gear b is secured from revolving in case B by set-screw t; so when shaft A is revolved pinion d is carried by eccentric D, on which it revolves, around the circle described by the toothed portion of gears b and c, and is caused to revolve on its own axis D, because gear b is fixed, as above mentioned. In so revolving, the teeth of said pinion successively encounter the teeth of gear c, which stand in a slightly differential position to those of fixed gear b, and thus force the teeth of gear c to a constantly-coinciding position with the teeth of gear b. This action of the parts just named causes gear c and the scroll-plate h, to which it is secured, to revolve on the axis thereof—viz., the projection o on shaft A—in the ratio of one to thirty, that being in this case the proportion of difference between the pitch of the annular gears, hence requiring thirty revolutions of the shaft A to effect a complete revolution of the scroll-plate h. Thus the jaws i are, by the well-known action of the scroll-plate thereupon, compelled to move simultaneously in lines toward the center and grasp the drill or other object intended to be held by the chuck. Reversing the movement of the shaft A causes the jaws i to open. Since the act of revolving the chuck upon shaft A, and vice versa, causes the jaws to

grasp the object held by it, it is obvious that any force which tends to carry the chuck farther around on its shaft in the same direction must cause the jaws thereof to gripe still 50 tighter. Hence it is that the tendency of a drill to turn in its chuck cause the drill to be held more tightly and prevent any slip between the jaws and the shank of the drill. 55 However tightly the chuck may have been forced upon a drill or other object, it cannot be so set beyond the power of the hand alone, grasping the case, to reverse and open it.

I am aware that differential gears have been used in hoisting-pulleys for the purpose of securing increased lifting capacity, and I make no broad claim to their use for increasing the power applied; but it will be seen that in the device above described the differential gear is 65 made the medium of applying a powerful pressure to the radially-moving jaws, whereby they can be caused to bite onto and hold the tool or article operated on with such force that it is practically immovable.

I claim—

1. In a lathe-chuck, the combination of clamping-jaws and scroll-plate, or its equivalent, and differential gear, constructed as set forth, and serving as a means of forcing the 75 said jaws with a powerful pressure upon the article to be gripped, as specified.

2. The combination, with the jaw-operating mechanism of a lathe-chuck, of the chuck-case B, the differential gears, consisting of the 80 gears b and c and pinion d, and shaft A, provided with the eccentric D, substantially as and for the purpose set forth.

3. The combination of shaft A, constructed as shown, the differential gears, consisting of 85 the gears b and c and pinion d, scroll-plate h, jaws i, case B, and nut e, substantially as and for the purpose set forth.

JAMES E. WILSON.

In presence of—

JOSIAH H. MACY,
F. W. HURD.
